Chas H. Smith

Inventor.

John W. Gay.

UNITED STATES PATENT OFFICE.

JOHN W. GAY, OF BROOKLYN, NEW YORK.

IMPROVEMENT IN MUFFS.

Specification forming part of Letters Patent No. 41,766, dated March 1, 1864.

To all whom it may concern:

Be it known that I, JOHN W. GAY, of Brooklyn, in the county of Kings and State of New York, have invented, made, and applied to use a certain Improvement in Muffs; and I do hereby declare the following to be a full, clear, and exact description of the said invention, reference being had to the annexed drawing, making part of this specification, wherein I have represented an end view of a muff formed with my improvement.

Muffs have heretofore been made with a lining of silk extending through the inside and over the ends to the edges of the fur covering. In some instances a strip of fur has been introduced at the middle of the inside of the muff, but this is liable to become moth-eaten, because not accessible for beating or brushing, and such linings admit cold air around the wrists.

The nature of my said invention consists in a ring or band of fur applied at the ends of the muff around the opening through said muff, which band of fur surrounding the wrists of the person carrying the muff excludes the cold air and renders the muff much more comfortable to the party using the same.

In the drawing, *a* represents the fur forming the outside of the muff. *b* is the silk or other lining passing through the muff and extending over the ends thereof and uniting to the edges of the fur *a*. *c* is a band of fur which is to be applied at each end of the muff and surround the opening through said muff. This band of fur may be sewed at this point upon the lining or introduced between the pieces forming the end and center parts of the lining, and if desired an elastic strip may be introduced to draw the fur-band more tightly around the wrist, but yield for entering or withdrawing the hand.

What I claim, and desire to secure by Letters Patent, is—

A muff formed with a band or ring of fur at each end of the opening through the muff, as and for the purposes specified.

In witness whereof I have hereunto set my signature this 3d day of December, 1863.

JOHN W. GAY.
